UNITED STATES PATENT OFFICE.

BERNHARDT E. HENRIKSEN, OF SAN FRANCISCO, CALIFORNIA.

BRIDGE FOR FIRE-HOSE.

SPECIFICATION forming part of Letters Patent No. 380,036, dated March 27, 1883.

Application filed January 7, 1883. Serial No. 260,085. (No model.)

To all whom it may concern:

Be it known that I, BERNHARDT E. HENRIKSEN, of the city and county of San Francisco, State of California, have invented an Improvement in a Bridge for Fire Hose; and I hereby declare the following to be a full, clear, and exact description of the same.

My invention relates to certain improvements in apparatus for supporting fire-hose, so that it may be carried across streets and railway-tracks without preventing or interfering with the passage of horses, vehicles, cable or steam cars, or other street traffic, the object being to provide a substantial bridge, which, while being light and portable, can be adjusted to suit any height of vehicle, grade of street, or unevenness of ground, and extended over any number of tracks or width of street, the construction being such that several lengths of hose may be carried over a single bridge.

Referring to the accompanying drawings for a more complete explanation of my invention, Figure 1 is a side elevation of one section. Fig. 2 is an end elevation of one of the yokes. Figs. 3 and 4 are enlarged views of the two yokes. Fig. 5 is a side elevation of the yokes of two connecting sections when jointed together.

In the construction of my bridge I employ yokes A and B, which are in the present case shown as semicircular in form, and these yokes have holes made through the upper ends, and also through the lower central portion of the curve, as shown in Fig. 2, so that rods C may pass through these holes, being suitably secured, so as to form a cradle of any desired length. I prefer that the rods C be made tubular in form for lightness and strength, and as many yokes D may be employed between the two end yokes, A and B, as are necessary to give the proper strength and stiffness to the structure. The end yokes, A and B, have inclined faces formed upon the outer sides near the upper ends, as shown at E, and screw-threaded bolts G extend outwardly from these faces and at right angles with them. Legs H, which are preferably made tubular for lightness, have heads I formed at their upper ends, with holes through them to fit over the bolts G, and the faces which come in contact with the faces E may be corrugated or roughened,

or otherwise so formed that they may be firmly locked by means of the clamping-nuts F, which turn upon the screw-bolts G. The legs will thus be held in place so that they cannot turn or move. These legs have telescopic sections or extensions J, which slide in or out of their lower ends, and which are held at any desired point by holding-screws K. When the legs are secured to the yokes, as shown in Figs. 1 and 2, they cross each other, and they may be united below the point of crossing by a chain, L, which will prevent their slipping or spreading under considerable weight.

In order to unite the ends of two sections together, each of the sections has a short bolt or pin, M, projecting so as to fit into corresponding openings in the adjacent yokes. Upon the top of one of the adjacent yokes are the upwardly-projecting lugs or hooks N, and upon the upper sides of the other adjacent yoke are the hinged latches O, having slots formed in them, so that they may, when turned down, hook through the lugs N, and thus unite the upper ends of the yokes firmly together. In the center and lower portion of the adjacent yokes are similar hooks and latches, P and Q, by which this portion is secured. By this construction it will be seen that as many sections of the cradle may be firmly united together as may be desired to carry the hose a considerable distance. If there is any unevenness or irregularity in the surface of the ground, or if it be desired to raise or lower the sections for any purpose, it is done by means of the adjustable leg-sections J. When not in use, these sections are separated, the legs H being turned up to fold alongside of the cradle, and one or more of the sections may be carried upon the hook-and-ladder truck or other vehicles of the fire department, or upon cars, the whole device being light and occupying but little space.

Should a fire occur and it become necessary to use one or more lines of hose across a street or line of railroad-tracks, one or more of these sections are taken from the trucks or cars and laid across the tracks or roadway and clamped together. As many lines of hose as it may be desired to use are next placed in the semicircular cradle or tube thus formed, and the bridge is raised to the required height by means

of the legs, which are then firmly secured by the clamp-nuts F, so that the structure cannot fall. When two or more sections are required, the yokes A of one section and B of the next adjacent section are united by the hooks and latches above described until as great a length of the structure has been erected as may be needed. In cases of necessity additional lines of hose can be readily placed upon the bridge already set up by means of suitable poles having forked or concave ends provided for that purpose. In some cases T or angle bars or other forms of connecting-rods may be used between the yokes; but I have found the hollow tubes to be the lightest and most rigid construction.

Having thus described my invention, what I claim as new, and desire to secure by Letters Patent, is—

1. A portable extension-bridge for fire-hose, composed of independent concave yokes having the ends constructed with lugs or connecting-latches, substantially as herein described.
2. The bridge or cradle sections composed of semicircular yokes having rods or tubes extending through them, so as to form concave bridges, in combination with legs pivoted to opposite sides of the end sections, so as to cross each other, and having the bolts and locking or clamping nuts by which they are secured to the yokes, substantially as herein described.
3. The concave yokes with the uniting rods

or tubes extending through them, so as to form cradle-sections, the legs having corrugated or roughened heads, which are secured upon corresponding inclined faces upon opposite sides of the end yokes of the sections, and the telescopic extensions of said legs, with the holding or clamping screws, substantially as herein described. 35

4. The concave yokes with the rods or tubes extending through them, so as to form bridge or cradle sections, and the adjustable supporting-legs with the clamping-nuts, in combination with the latches and the lugs or hooks upon adjacent meeting sections, whereby they 45 may be united together to form an extension-bridge, substantially as herein described. 40

5. The concave yokes with the uniting rods or bars, the adjustable supporting-legs, and the lugs and latches by which adjacent meeting ends of the sections are united together, in combination with the projecting pins or bolts M, whereby the tubular bars are united and made continuous from one section to the other, substantially as herein described. 50 55

In witness whereof I have hereunto set my hand.

BERNHARDT E. HENRIKSEN.
